UNITED STATES PATENT OFFICE.

FRANK J. HINDERLITER, OF TULSA, OKLAHOMA.

JOINT BREAKER.

Application filed February 13, 1922. Serial No. 536,067.

To all whom it may concern:

Be it known that I, FRANK J. HINDERLITER, a citizen of the United States, and a resident of the city of Tulsa, in the county 5 of Tulsa and State of Oklahoma, have invented certain new and useful Improvements in Joint Breakers; and I do hereby declare that the following is a full, clear, and exact description of the same, reference being had 10 to the accompanying drawings, and to the numerals of reference marked thereon.

This invention relates to an apparatus designed for uncoupling pipes, rods, or the like, pertaining especially to well drilling 15 appliances, commonly known as joint breakers.

In the past, these apparatus usually involved lever operated ratchet jacks which required a good deal of power. Frequently, 20 several men were necessary to operate the same for breaking a tight screw-threaded joint, and they were limited in their application of power.

My invention is designed to overcome 25 these defects and produce an apparatus which will produce a large amount of power with the application of little force, whereby one man can accomplish that which usually required the services of several.

My invention comprises the novel structures and combination of parts hereinafter described and more particularly pointed out and defined in the appended claims.

In the accompanying drawings which 30 illustrate a preferred embodiment of my invention and in which similar reference numerals refer to similar features:

Figure 1 is a top plan view of an apparatus for breaking screw-threaded joints involving my invention.

Figure 2 is a view showing the development of the curved rack bar with the jack and stop member in elevation.

Figure 3 is an enlarged front elevation of 45 the jack attached to the rack bar which is shown in section.

Figure 4 is a section on the line 4—4 of Figure 3.

Figure 5 is a bottom plan view of the 50 jack upon a reduced scale.

In the accompanying drawings, I have 55 illustrated a support 1 for supporting a T-shaped arcuate rack 2 which may be secured to the support in any appropriate manner. A portion of the upper surface of

the rack bar is provided with inclined ratchet teeth and upon the toothed periphery there is an adjustable stop member 3 provided with a pawl (not shown) for engaging the ratchet teeth. The construction of this 60 stop is well known and need not be further described.

One portion of the arcuate rack bar has an upper smooth surface 4 preferably located adjacent one terminal thereof, in which a 64 plurality of holes 5 are bored for adjustably supporting the joint breaking jack 6.

This jack comprises a body portion 7 having an opening in its upper portion to provide a handle and having a smooth bore 76 extending therethrough, a portion of the bore being reduced at the rear of the body portion to provide an annular shoulder 8 and the front end of the bore being provided with a key groove 9. The body portion 7 is provided with a slightly curved T-shaped grooved base 10 which fits and is adapted to slide on the smooth portion 4 of the rack bar 2 and a pair of bolt holes 11 are provided in the base for anchoring the 80 jack against longitudinal movement on the rack bar by means of bolts or screws inserted through the holes 11 and 5. A removable and replaceable interiorly threaded bushing 12 having a key or lug 13 fitting 85 the groove 9 is located in the bore and anchored against rotation by said lug 13 and abuts against the annular shoulder 8.

A jack screw 14 is threaded into the sleeve 12. This jack screw is provided with an 90 exterior boss 15 having a plurality of handle sockets 16 for receiving an operating handle or lever. Centrally of the boss, there extends a stub shaft 17 having a groove 18 adjacent its outer end and concentric with the stub shaft 17. The boss 15 is provided with a ball groove. A thrust head 19 is rotatably supported upon the stub shaft 17 and is provided with a key 20 that operates in the groove 18 and rotatably retains the head on the stub shaft. The inner surface of the thrust head is provided with a ball raceway opposite the raceway in the boss 15 and a series of anti-friction balls 21 are supported in the raceway and take the thrust. Consequently, very little friction will be engendered between the stationary head and the jack screw during the operation thereof. The front face of the thrust head 19 is bifurcated in order to securely retain a 110

wrench handle or the like which it is intended to operate.

Concentrically of the arcuate rack 2, the support 1 is provided with an aperture 5 through which projects the jointed pipe or rod having the threaded joint that it is desired to unscrew.

In using this apparatus, a pair of long wrenches 22-22^a such as shown in Figure 10 1 are secured upon opposite sides of the joint of the rod or pipe above the support 1; the handle of one wrench engaging the stop 3 and the handle of the other wrench engaging the thrust head 19. Rotation of the screw 15 14 in the proper direction by a lever inserted in one of the apertures 16 will advance the jack screw and wrench handle to uncouple or break the joint of the jointed rod or pipe as is obvious. It is evident that comparatively little force is required to operate the 20 jack screw and that it can be easily adjusted to take up lost motion and bring the thrust head into contact with the wrench handle if the same has not originally been brought 25 snugly against the head.

It is characteristic of my invention that the wear and tear of the jack is absorbed by a removable bushing which can be readily replaced and that a single individual can 30 exert sufficient power on the jack to break the tightest joint, do it more quickly than in devices formerly used, that the T-shaped groove connection with the rack 2 produces a binding effect during operation, and thus- 35 wise assists in holding the jack in position.

I am aware that numerous details of construction may be varied through a wide range without departing from the principles of this invention and I therefore do not pur- 40 pose limiting the patent granted otherwise than necessitated by the prior art.

I claim as my invention:

1. In an apparatus of the class described, an arcuate rack having a smooth portion and a serrated portion, an adjustable stop 45 on the serrated portion, and a screw jack on the smooth portion.

2. In an apparatus of the class described, an arcuate rack having a smooth portion, a screw jack having a T-shaped groove slid- 50 ably fitting said smooth portion, and means for anchoring said jack in adjusted position.

3. In an apparatus of the class described, a support, an arcuate rack upon said support, a stop adjustable on said rack and 55 adapted to restrain movement in one direction, and rotatable means opposed to said stop and adapted for operating a lever toward said stop.

4. A jack screw having a body portion 60 and a base portion provided with a T-shaped groove, said body portion having a horizontal cylindrical bore and an annular shoulder therein, a removable bushing in said bore abutting said annular shoulder, 65 and a jack screw threaded in said bushing and having a rotatable anti-frictionally mounted thrust head thereon.

5. A jack screw comprising a body portion, a horizontal cylindrical bore in said 70 body portion, a screw threaded jack shaft in said bore, and a rotatable thrust head anti-frictionally supported on said jack shaft and having a bifurcated front surface adapted for receiving and operating a lever. 75

In testimony whereof I have hereunto subscribed my name in the presence of two subscribing witnesses.

FRANK J. HINDERLITER.
